UNITED STATES PATENT OFFICE.

WILLIAM SIBERT WITTER, OF RIDOTT, ILLINOIS.

CHAIR-SWING.

SPECIFICATION forming part of Letters Patent No. 657,188, dated September 4, 1900.

Application filed March 22, 1900. Serial No. 9,712. (No model.)

To all whom it may concern:

Be it known that I, WILLIAM SIBERT WITTER, a citizen of the United States, residing at Ridott, in the county of Stephenson and 5 State of Illinois, have invented a new and useful Chair-Swing, of which the following is a specification.

The usual construction of chair-swings, to which general class of devices my invention 10 appertains, has comprehended the employment of a frame embodying a portable base and a high superstructure, from which latter depend the pendant-supports of one or more swinging chairs. Swinging motion is im- 15 parted to the pendants by a swinging movement of the body of the occupant, and the chair bottoms or seats are ordinarily mounted in a manner to permit the operator or occu- 20 pant to exert his strength to change the angular relations of the pendants with respect to a movable foot-rest pivoted to the pendants and against which the feet of the operator are braced. This muscular effort, intermittently applied, serves to augment the sway- 25 ing of the body to maintain the motion of the swing. The cumbersome nature of this structure precludes the possibility of its general use indoors, and the high superstructure renders it unstable and liable to topple over in 30 the event of violent swinging.

The primary object of my present invention therefore is to devise a portable chair-swing embodying a comparatively-small supporting-frame having no superstructure extending above the occupant and capable of 35 being swung through power applied by either the arms or legs of the occupant, or both, as desired.

A further object of the invention is to render the chair-backs adjustable and to provide for the ready conversion of the device into a swinging bed or cradle.

To these ends the invention consists in suspending a light platform from pendants swung 45 from the upper ends of movable standards pivotally supported by a portable base, the front and rear chair supports or legs being pivotally connected to the pendants and platform, respectively.

50 The invention further consists in extending the pendants above their pivotal supports, where they terminate in handles, and

finally in providing means for changing the inclinations of the backs and for permitting them to be turned down into horizontal positions between the adjacent edges of the seat to effect the conversion of the device for use 55 as a child's bed or cradle.

Referring to the accompanying drawings 60 illustrative of a structural embodiment of the invention, Figure 1 is a side elevation of my swing complete, an adjusted position of one back being indicated in dotted lines. Fig. 2 is a longitudinal sectional view showing in dotted lines the horizontal position of a back 65 to form a couch or bed. Fig. 3 is a sectional end elevation of the swing. Fig. 4 is a detail perspective view of a chair and its supports; and Fig. 5 is a detail view of one of the front supports.

70 Referring to the numerals of reference indicating corresponding parts and structural characteristics in the several views, 1 indicates a portable base of any desired construction, but preferably composed of side rails 2, 75 set on edge and connected by transverse bars 3, properly located to permit of the interpolation of a movable platform 4 between the rails. This platform, which is, broadly speaking, a movable seat-supporting member, is 80 preferably somewhat shorter than the base and is composed of side bars 5, connected and / spaced by a number of transverse slats 6, secured at their opposite ends upon the upper edges of the bars 5 and located in a slightly- 85 higher horizontal plane than the steps 7, formed by a horizontal longitudinal strip nailed or otherwise secured upon the rails of the base. The platform is further strengthened by light transverse bars or shafts 8, 90 preferably square in cross-section and having cylindrical ends projecting through and beyond the sides of the platform and constituting pintles 9 for the lower ends of pendants 10, swinging from what may properly be termed 95 "fulcrums," as the upper ends of the pendants are extended to form handles 12, thus converting them into levers, which are manually operated in a manner to be noted to impart a swinging movement to the platform 100 and its connected parts.

Between each pair of pendants 10 is pivotally supported a chair, the seat 13 of which is provided with relatively-fixed and prefer-

ably-braced front supports or legs 14 and terminally-pivoted rear supports or legs 15. The precise manner in which these parts are assembled is not essential; but the rear supports are preferably retained by transverse bars 16, extending between and through the seat-bars 17 of the seat, and by transverse bars or shafts 18, similar to the bars 8 and likewise terminating beyond the sides of the platform to constitute pintles 19 for the lower ends of the rear supports.

The front chair-supports 14 terminate a short distance above the platform, and each pair is pivotally connected at its lower end to the adjacent pendants or levers 10, as by a shaft 20. The upper ends of the front supports are extended above the seats somewhat to serve as supports for the chair-arms 21, pivotally secured thereto, and likewise pivotally connected at their rear ends to the opposite sides of an angularly-adjustable and reversible chair-back 22. Any suitable means may be employed for the purpose of securing this adjustability and reversibility of the back; but a simple manner of accomplishing the desired end is to form a terminal recess 23 in each side bar of the back and designed to detachably retain the back in its various angular positions by engagement with the bar 16 or with any desired back-retaining lug 24, a series of which project horizontally from each seat-bar 17.

The structure thus far described is complete and operative, since it will appear that swinging motion may be imparted to the platform and the various parts carried thereby through the exertions of the occupant or occupants of the chair or chairs; but I desire to augment or magnify the movement ordinarily obtained by suspending the pendants from supports which are themselves capable of more or less movement. These supports for the pendants I will term "vibrating standards" because their movement is necessarily restricted and amounts to little more than vibration, which, however, being effective at the point of suspension is productive of considerable acceleration of movement at the opposite end of the element suspended. Each vibrating standard is composed of two pairs of downwardly-divergent standard-bars 25, each pair being located just inside of one of the base-rails 2 and bifurcated at their upper ends, as indicated at 26, for the reception of the opposite extremities of a short horizontal pendant-supporting link 26°, pivotally connected to each bar 25 and made rigid with a bracket 27, projecting from and fixed to the adjacent pendant 10 just below its handle. The lower ends of the transversely-opposed bars 25 of the two pairs constituting a set or standard—that is to say, the front or rear bars, as the case may be—are rigidly connected to transverse rock-shafts 28, extending between and journaled in the base-rails 2 below the platform 4. Thus it will appear that the movement of the corresponding

standard-bars will be identical and that the vibration of the fulcrums or points of suspension of the pendants will be limited to the difference between the combined dimensions of the sides of the angle formed by a bar and link and the hypotenuse of such angle, since the mounting of the bars on different centers limits their pivotal movement to the accommodation afforded by the link therefor.

It may be noted that the present embodiment of my invention comprehends two oppositely-disposed seats or chairs identically constructed and mounted; but it is obvious that the device would be equally operative with a single chair or with more than two, as each chair is independent of the other, while the occupant of each may contribute to propulsion of the swing.

In brief, the operation of the swing is as follows: The occupants seated in the chairs with their feet resting upon the platform grasp the handles 12 of the pendants or operating-levers and by pushing with the feet and pulling upon the handles exert force tending to change the relative angle of the platform with respect to the pendants. This of course can not be done without swinging or oscillating the pendants, since the platform is suspended from a plurality of points by pendants of equal length, and consequently cannot be urged out of its horizontal position. The force thus exerted is discontinued as soon as slight motion is imparted to the platform, which then swings back, and its return is then effected by a reapplication of power, which is now augmented by the impetus gained. The intermittent continuation of the foregoing operation serves to maintain or increase the swinging movement, as the case may be.

It has been stated that the operator simultaneously pushes with the feet and pulls with the arms, the reason for this being that the forces thus exerted are applied to the pendants or levers 10 at opposite sides of their fulcrums, and it will be evident therefore that either or both of these means of propulsion may be employed, as desired. The weight of the occupant is likewise utilized, as the rigid connection of the seat and its front support constitute one member of a toggle-lever, the other member of which is the rear support 15, the ends of the toggle being at the axes thereof of the shafts 18 and 20, and the knuckles at the axis of the shaft 16.

In Fig. 2 of the drawings I have illustrated in dotted lines how a back 22 may be swung upon the arms 21, and turned down or reversed into a horizontal position, resting upon the edges of the back seats and closing the space between the seats to convert the device into a child's bed.

From the foregoing it will be observed that I have produced a portable chair-swing of simple and durable construction by means of which I attain the various objects herein stated; but while the embodiment of the in-

vention described and illustrated is believed at this time to be preferable I desire to reserve the right to effect such changes, modifications, and variations as may come properly within the scope of the protection prayed.

Therefore what I claim, and desire to secure by Letters Patent, is—

1. A swing comprising a stationary base, standards pivotally connected to the base, 10 pendants pivotally connected to the upper ends of the standards, a seat, and pivoted seat-supports, one of which latter is rigidly connected to the seat and is pivotally connected to the pendants at a point below the seat.

2. The combination with a suitable support, of swinging pendants, a platform carried by the pendants, pivoted seat-supports, one of which latter is rigidly connected to the seat 20 and is pivotally connected to a pendant at a point below the seat, and operating means located above the seat and operatively connected with one of the pendants.

3. A swing comprising a support, swinging 25 pendants carried thereby, one of said pendants being extended above its point of suspension to form an operating-handle, a movable platform supported by the pendants, a seat, and means operatively connecting the seat with the pendants and platform, respectively.

4. The combination with a suitable support, swinging pendants, and a platform carried by the pendants, of a seat having front and rear 35 supports pivotally connected to the pendants and platform respectively, and an operating-handle operatively related to one of the pendants.

5. The combination with a supporting-pendant, of a seat, a seat-support pivotally connected to the pendant below and extended above the seat and connected to the seat adjacent to its front edge, an arm-rest carried by the extended upper end of the support, 45 and means for supporting the rear edge of the seat.

6. The combination with a base and vibrat-

ing standards, of pendants suspended from the upper ends of the standards and extended above their points of suspension to form operating-handles, a platform carried by the pendants, a seat provided with a relatively-rigid front support pivotally connected to the pendants above the platform and with a relatively-movable rear support pivoted to the platform.

7. In a swing of the class described, the combination with the base, of movable standards connected with the base and arising therefrom, swinging pendants pivotally suspended 60 from said standards and extending thereabove to form operating-handles, a platform sustained by said swinging pendants, and oppositely-arranged seats provided with depending front and rear supports of different 65 lengths, the front supports of the seats being pivotally connected to the pendants, and the rear supports thereof being pivotally connected with the platform, substantially as set forth.

8. The combination with a pendant, a seat-support pivoted thereto, and a seat connected to said support, of an arm-rest pivoted at one end to the seat-support, a back pivotally connected at an intermediate point to the opposite end of the arm-rest, and means for adjustably connecting the back with the seat.

9. The combination with a pendant-support, of a seat, a seat-support rigidly connected to the seat and pivotally connected to 80 the pendant below said seat, an arm-rest connected to the seat-support above the seat, a back pivotally connected to the opposite end of the arm-rest, and means for effecting a detachable pivotal connection between one edge 85 of the back and the seat.

In testimony that I claim the foregoing as my own I have hereto affixed my signature in the presence of two witnesses.
